Primary Examiner—Wallace R. Burke*Assistant Examiner*—Lavone D. Tabor*Attorney, Agent, or Firm*—Herbert C. Schulze**[57]****CLAIM**

The ornamental design for a cleaning head for gun barrels, as shown and described.

DESCRIPTION

FIG. 1 is a perspective view of a cleaning head for gun barrels showing my new design;

FIG. 2 is a front elevational view thereof;

FIG. 3 is a left side elevational view thereof, the right side elevational view and the top and bottom plan views being mirror images; and,

FIG. 4 is a rear elevational view thereof.

The broken line showing of a hose in FIG. 1 is for illustrative purposes only and forms no part of the claimed design.

FIG. 1.

FIG. 2.

FIG. 3.

FIG. 4.
